CYLINDER PLUG FOR GAS-OPERATED GUNS
WITH GRENADE LAUNCHERS

Charles H. Coates, Baton Rouge, La.

Application January 31, 1945, Serial No. 575,530

5 Claims. (Cl. 42—1)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to an improved gas cylinder plug for gas operated semi-automatic type rifles and it is especially designed for adapting such rifles to use with grenade launchers.

When rifles of the above described type are used in conjunction with grenade launchers for launching rifle or hand grenades, some means must be provided to reduce or eliminate the gas pressure which is produced in the gas cylinder of the piece, incident to the firing of the same, for the reason that the failure to do so will result in the piston rod in the cylinder being driven back with sufficient force to damage the working parts of the weapon.

As a result, a special grenade launcher and a special gas cylinder plug, to be used in conjunction therewith, has been developed for the rifle. This plug is equipped with a valve which is held in an open position by a part of the grenade launcher, when the latter is applied to the rifle, to permit a portion of the gases, entering the gas cylinder, to escape therefrom through the gas cylinder plug, to thereby substantially reduce the pressure in the gas cylinder when ordinary ammunition is fired and thereby prevent the actuation of the piston rod.

However, it is an object of this invention to provide an improved gas cylinder plug for the same purpose as the above described plug, but constructed to function in an entirely different manner, whereby the valve in the plug will be moved to a closed position by a part of the grenade launcher to entirely close the intake port of the gas cylinder so that no gases will be admitted thereto.

A particular advantage of the present invention resides in the fact that none of the gases and the carbon carried thereby come into contact with the working parts of the plug, so that the parts are not damaged by the hot gases and their operation is not impeded by an accumulation of carbon.

Various other objects and advantages of the invention will hereinafter become more fully apparent from the following description of the drawing, which illustrates a preferred embodiment thereof, and wherein:

Figure 1 is a longitudinal side elevational view, partly in section, of a portion of gas operated semi-automatic type rifle equipped with a con-

2

ventional model M7 rifle grenade launcher and the improved plug; and

Figure 2 is a similar view showing the parts with the grenade launcher removed.

Referring more particularly to the drawing, wherein like reference characters designate like or corresponding parts throughout the different views, for the purpose of illustrating one form of the invention, a portion of a semi-automatic gas operated rifle and a rifle grenade launcher have been shown. These parts include the forward portion of the rifle barrel 3, a false muzzle 4 having a bore of slightly greater diameter than that of the barrel 3, and which is connected to the forward end thereof by a socket member 5, which forms a part of the gas cylinder 6. A piston rod 7 is slidably mounted in the gas cylinder 6 and its forward end extends into the reamed out forward end 8 of the gas cylinder, which accommodates the gas cylinder plug. A conventional rifle grenade launcher 9 is shown mounted on the forward end of the rifle and latched thereto in the conventional manner by engagement with the bayonet stud 10 thereof. The launcher is only modified in that the rear end of its bore is reamed out to receive the forward end of the false muzzle 4, which is larger externally than the muzzle of the rifle. The parts previously described form no part of the present invention but have been disclosed for the purpose of better illustrating the construction and operation of the improved gas cylinder plug, designated generally 11, and comprising the invention.

The gas cylinder plug 11 includes a housing 12 having a bore 13 opening outwardly at each end thereof and separated intermediate of its ends by a transverse wall or partition 14 having a centrally disposed communicating opening 15 of a smaller diameter than the bores 13. The plug 11 is mounted in the reamed out end 8 of the gas cylinder 6 and the inner bore 13 contains a sleeve or bushing 16 having an intake port 17 which is disposed for communication with an intake port 18 of the housing 12. The muzzle of the barrel 3 is spaced slightly from the adjacent end of the false muzzle 4 to provide a passage 19 which communicates with the intake port 18 to thereby form a gas passage from the bore of barrel 3 to the portion of the gas cylinder, formed by the sleeve or bushing 16. A valve, designated generally 20, is provided with a piston-like head 21 which is slidably mounted in the bushing 16 and which has a stem 22 extending therefrom through opening 15 and disposed for sliding engagement therewith. The opposite end of the stem 22,

which is disposed in the outer end of the bore 13, is provided with a head 23 forming an abutment for one end of an expansion coil spring 24 the opposite end of which bears against the partition 14 for urging the valve 15 forwardly and into an open position, as seen in Fig. 2. Housing 11 is provided with an upwardly extending, substantially semi-circular finger 25 which seats in an annular groove 26 in the false muzzle 4 for detachably retaining the plug 11 in position in the gas cylinder 6.

From the foregoing, it will be apparent that when the grenade launcher 9 is applied to the rifle, as shown in Fig. 1 and as previously described, its stud 27 will engage the head 23 to depress the valve 20 inwardly and to its position of Fig. 1. With the valve 20 thus disposed, its piston 21 will close and seal intake port 17 to prevent the propelling gases from the bore of the barrel 3 from passing through the intake port 17 into the sleeve 16. Consequently, the gas actuated piston 7 will thus be rendered inoperative and will remain in its forwardmost position, as illustrated, substantially in engagement with the piston 21, so that the bolt of the rifle, not shown, will have to be manually operated for extracting, ejecting and loading either propelling cartridges or ball ammunition. When the grenade launcher 9 is removed, valve 15 will be biased to its open position of Fig. 2 by spring 24, thereby exposing the intake port 17 and forming a chamber between piston 21 and piston 7 in the sleeve 16 to receive the expanding propelling gases. When thus disposed, piston 21 will function as a fixed cylinder head and the gas piston 7 will be driven rearwardly by the expanding gases for automatically operating the rifle bolt in the conventional manner.

Thus, it will be obvious that the hot propelling gases will be at all times excluded from the valve stem 22, opening 15, spring 24 and the rear portion of sleeve 16, so that these parts will not be damaged thereby and will not become coated with an accumulation of carbon carried by the gases.

Various other modifications and changes are likewise contemplated and may be resorted to without departing from the spirit and scope of the invention as hereinafter defined by the appended claims.

I claim:

1. In a gas operated weapon having a barrel means, means therein forming a gas passage, a gas cylinder means on said barrel means having a gas port in register with said gas passage and

5 a piston rod slidably associated with the gas cylinder means, the combination therewith of a piston mounted in the gas cylinder means for sliding movement therein to cover the gas port when adjacent the piston rod and to uncover the gas port when spaced from said piston rod, a grenade launcher on the barrel means, and means on the grenade launcher engaging said piston to move the same adjacent the piston rod to cover the gas port whereby said piston rod is rendered inoperative.

2. In the combination as set forth in claim 1, means associated with said piston yieldingly biasing the same away from the piston rod to port uncovering position.

3. In a gas-operated firearm having a barrel means, means therein forming a gas passage, a gas cylinder means on the barrel means having a gas port in communication with the gas passage and a piston rod in the gas cylinder means, the combination therewith of a plug in the gas cylinder means, a medial partition in said plug and provided with a central orifice, a sleeve in one end of said plug abutting said medial partition and slidably receiving the piston rod, said sleeve having a port communicating with the gas port, a piston slidably mounted in said sleeve and having a reduced portion slidably received in said central orifice, said piston closing the port in the sleeve when the piston is adjacent the piston rod and opening the gas port when said piston is adjacent the said medial partition.

4. In the combination set forth in claim 3, and resilient means yieldingly biasing said piston against the medial partition.

5. In the combination set forth in claim 3, and resilient means biasing said piston against the medial partition, a grenade launcher mounted on the barrel means, and a portion on said grenade launcher engaging said piston for holding the piston in port covering position against the bias of the resilient means.

CHARLES H. COATES.
